Inventor:
Neal W. Plooster

UNITED STATES PATENT OFFICE.

NEAL W. PLOOSTER, OF PRESCOTT, ARIZONA.

BRUSH.

Application filed March 30, 1925. Serial No. 19,492.

To all whom it may concern:

Be it known that I, NEAL W. PLOOSTER, a citizen of the United States, residing at Prescott, in the county of Yavapai and State 5 of Arizona, have invented new and useful Improvements in Brushes, of which the following is a specification.

This invention has reference to a shoe 10 polishing device, and has for its object to provide a polishing pad or brush with a cover of backing of flexible material of such construction and arrangement that the same may be arranged around the pad to fully 15 enclose the same, whereby the device may be conveniently carried in the pocket of the user, the said backing being also designed to be looped upon itself over the pad to provide a hand strap for manipulating the pad, simple means being provided for securing the 20 backing in either of its mentioned positions.

The improvement embodies other novel 25 features of construction which will be set forth in detail in the following description, illustrated by the accompanying drawings, and pointed out with particularity in the appended claim.

In the drawings:—

Figure 1 is a perspective view of the improvement.

Figure 2 is an approximately central longitudinal sectional view therethrough.

Figure 3 is a substantially similar section, but showing the pad cover of backing looped upon itself to provide a hand hold.

35 In the drawings I have illustrated the pad

1 provided with a facing 3 of soft material, such as lamb's wool.

The flexible or non-flexible face 1 of the pad is secured in any approved manner adjacent to one end of a backing 3. The backing or cover may be made of leather, composition or other flexible material, and the same is of a length to be arranged entirely around the pad, as illustrated in Figures 1 and 2 of the drawings. When so arranged, 40 the ends of the pad are connected together by any desirable means, such as indicated by the numeral 4 in the drawings. The backing 3 is also of a length whereby the same may be looped over the pad, it provides a 45 hand hold whereby the pad may be manipulated for shining or polishing shoes or other articles, and when the pad is enclosed in the backing as disclosed by Figures 1 and 2, 50 danger of the said pad soiling the garment 55 of the user will be effectively overcome.

Having described the invention, I claim:

A shoe polisher comprising a flexible backing, a pad secured to one face of said backing adjacent one end thereof, said backing being of a length to permit of the same being folded entirely around the pad to enclose the said pad or to be looped upon itself over the pad to provide a hand hold, and cooperative means carried by the ends of the 60 backing for detachably retaining the ends of the backing in either of said positions.

In testimony whereof I affix my signature.

NEAL W. PLOOSTER.
